ABSTRACT OF THE DISCLOSURE

A process for the dissolution of sodium, potassium and/or their alloy after irradiation in which the material for dissolution is subjected to the action of alcohol in an argon atmosphere the reaction taking place in the presence of a liquid soluble in any proportion in the alcohol, the amount dissolved being determined to control the reaction. Apparatus for carrying out that process including sleeves to engage the ends of an irradiation capsule holding the material, one sleeve being coupled to a fluid inlet and the other, via a valve to a tank which has an inlet for argon, a safety valve and two glove-box temperature measuring points.

The invention relates to a process and apparatus for dissolving sodium, potassium and their alloys, after the latter have been irradiated, generally while contained in an irradiation capsule. The invention is more particularly concerned with a process and apparatus of this kind for dissolving the equi-atomic alloy of sodium and potassium, NaK, in an alcohol under an inert argon atmosphere.

We have used such a process and apparatus for a long time and have found the process satisfactory for amounts of NaK up to 200 cm.³, it has disadvantages or is even dangerous when the amount of NaK exceeds 200 cm.³, as is the case with larger capacity irradiation assemblies which have since come into use, since the reaction of the alcohol on the NaK is highly exothermic, and when the amount of NaK reaches 400–600 cm.³, as it often does, the existing process and apparatus become inadequate to dissipate the excess heat of reaction which then very quickly becomes uncontrollable: the alcohol boils; the alcohol vapors, mixed with the hydrogen formed, evolve violently; the alcohol overflows and lifts the lid of the receptacle whose section is too small. Clearly, this method is risky, having regard to the relatively large amount of alcohol (of the order of 20 liters) which must be used to dissolve the NaK completely.

It is the main object of the invention so to adapt the processes and apparatuses of the kind specified that they meet more satisfactorily than hitherto various practical requirements, *inter alia* enable the dissolution reaction to be controlled and performed in an improved apparatus which increases safety and saves time and raw materials, as regards the total amount of alcohol used.

The main feature of the process according to the invention is that it consists in subjecting sodium, potassium and/or their alloy to the action of an alcohol in an inert argon atmosphere, the reaction taking place in the presence of a liquid soluble in any proportion in the alcohol, the reaction being controlled by varying the amount of alcohol dissolved in the liquid.

The invention also relates to an apparatus for the performance of the process, the apparatus being characterized in that it comprises two sealing-tight sleeves which can be connected to the two ends of an irradiation capsule containing the sodium, potassium and/or their alloy to be dissolved, the first sleeve being connectable to a fluid inlet pipe and the second sleeve being connectable

2

via a spherical plug valve to the lid of a wide-aperture tank, the lid, disposed on the tank without any gasket, comprising a shaft connecting with a tube of the plug valve, an argon inlet continued in the form of a tube whose lower portion is curved and which extends into the tank, and a safety valve, the tank having two glove-box temperature measuring points disposed in parallel and downwardly orientated at an angle of 45° with the tank wall.

10 Apart from these main features, the invention also relates to certain other features which are preferably used simultaneously, *inter alia*:

The liquid soluble in any proportions in the alcohol is a kerosene-based machining fluid;

15 The sealing-tight sleeves are of the kind disclosed in the French patent application filed in the applicants' name on Sept. 16, 1969 for: "Sealing-Tight Connecting Sleeve;"

The spherical plug valve is of the direct-control and 1/4-turn open-close type;

20 The lid has a flange to locate it on the tank;

The connecting shaft in said lid comprises laterally a wing-type point screw to lock the valve tube against rotation;

25 The lower portion of the curved tube is tangential to both the bottom and wall of the tank and is flattened in duck's bill shape at its end;

The lid has ribs at 90° along its radii, the ribs being formed with large-diameter holes enabling the lid to be handled,

30 The tank is cylindrical;

The side wall of the tank comprises two diametrically opposite lifting lugs;

The lower portion of the tank comprises a telemannipulation point, *inter alia* a ring;

35 The top edge of the tank comprises a pouring lip.

In any case, the invention will be clearly understood from the following description, with reference to the accompanying drawings, both description and drawings being merely exemplary and non-limitative, in which:

40 FIG. 1 is a vertical sectional view of the apparatus according to the invention, and

FIG. 2 is a detail of one of the sealing-tight connecting sleeves used in the apparatus illustrated in FIG. 1.

45 As already stated, it is an object of the method according to the invention to enable the dissolution reaction to be controlled.

50 As a rule, when sodium, potassium or NaK is placed in alcohol, it is found to react immediately, rise to the surface, thus limiting the volume of useful alcohol, and agglomerate in clots.

To control dissolution, steps must therefore be taken to retard, start, stop and perform the reaction as required, and then to dissipate the heat evolved.

55 To retard the reaction and prevent the NaK (or Na, or K) from reacting spontaneously with the alcohol on its emergence from the irradiation capsule or even therein, it is driven out with a chemically inert liquid and received in the same liquid.

60 To start the reaction at the required time, it is enough for the liquid to be soluble in any proportions in the alcohol, since the dissolution of the NaK which the liquid contains can then be started by adding a suitable amount of the alcohol thereto.

65 The reaction stops automatically when there is no longer enough alcohol in the solution.

To perform the reaction as required, it is then enough to add alcohol in small amounts, thus also enabling the reaction temperature to be controlled.

70 The reaction takes place at the surface of the liquid, the heat will be more readily dissipated in proportion as the receptacle section is increased (thus also reducing

the risk of convection) and the specific mass and exchange surface are also increased, and in proportion as a volume of inert, preferably non-flammable liquid is available in adjustable amounts to homogenize the temperature, and the liquid is continuously violently agitated to prevent hot spots and break up the large lumps of NaK. If agitation is performed by a gas stream the temperature can also be lowered as required by the output.

The apparatus illustrated in FIG. 1 enables the process disclosed hereinbefore to be performed under the conditions described hereinbefore. More particularly, the apparatus has been designed in accordance with the need to have a large section and not to be obliged to evacuate excessive amounts of liquids after each dissolution.

Referring to FIG. 1, the apparatus is mainly formed by a wide aperture tank 1, a lid 3, a plug valve 5, and two sealing-tight sleeves 7a, 7b.

The cylindrical tank 1 is made of rust-resistant steel. Its diameter is such as to contain substantially one liter of liquid per centimeter of height thus producing, for instance, the following dimensions:

	Mm.
Diameter	360
Height	202
Thickness	2

The upper portion of the tank has two diametrically opposed lifting lugs 9 welded to the sides, with enough lateral projection not to obstruct the lid 3, the lower portion of the tank having a ring, or more generally a telemannipulator point (not shown) adapted to facilitate the emptying of the tank by pouring when the tank is suspended from the lifting lugs 9.

Two glove-box temperature measuring points 11 are disposed on a generatrix of the cylinder of the tank 1 and can receive a thermometer or thermocouple. The measuring points are disposed in parallel and downwardly orientated at an angle of 45°; they enable the temperature to be taken at the bottom and on the surface of the liquid, whatever the amount thereof may be, up to an amount of 12 liters, with a tank of the size given by way of example.

The top edge of the tank 1 can be outwardly curved to form a pouring lip (this feature is not shown).

The rust-resistant steel lid 3 is simply placed without a gasket on the tank 1 on to which it fits and is located by its flange 13.

The lid 3 has at its center a shaft 15 adapted to receive with slight clearance tube 17 of a plug valve 5. The shaft 15 comprises laterally a wing-type set screw 19 enabling the tube 17 to be locked against rotation. The shaft 15 is shouldered on four ribs, as 21, at 90° radii.

The end of a rib 21 is formed with an argon inlet comprising in the upper portion of the lid 3 a self-sealing connection 23, and at the lower portion of the lid 3 a vertical rust-resistant steel tube 25 whose lower portion 27 is curved to be tangential both to the bottom and wall of the tank 1, the end of the tube 25 being flattened in a "duck's bill" 29.

Disposed at 90° from the argon inlet at the end of another rib 21 is a safety valve 31.

The ribs 21 are formed with large-diameter holes, as 33, to facilitate the handling of the lid 3.

The plug valve 5 and the sealing-tight sleeves 7a, 7b temporarily restore air-tightness to irradiation capsule 35 when its ends have been cut off, and also bring the capsule 35 filled with NaK in a direct and controlled manner into communication with the tank 1 and fluid inlet 37 at the right moment.

The plug valve 5 has a direct control 39 and is of the 1/4-turn open-close type. The plug valve 5 is continued in its lower portion by the tube 17 adapted to extend through the shaft 15 of the lid 3. The tube 17 is so machined that it can readily slide in the shaft 15 and take up position directly at a satisfactory height above the bottom of the tank 1. The upper portion of the valve

5 has a male tubular tip 41 and is normally always retained in the closed position.

The identical sealing-tight sleeves 7a, 7b are adapted to obliterate the cylindrical irradiation capsules 35 after their ends have been cut off, whatever the diameter of the capsules may be. The end of each sleeve 7a, 7b has a female self-sealing connection 43a, 43b respectively. The other end of the fluid inlet 37 also has a self-sealing connection 45 enabling the inlet 37 to be connected either to an inert liquid reservoir or a pure argon expanding station.

In the embodiment described, the sealing-tight connecting sleeves used are of the kind which will now be described with reference to FIG. 2, which is an axial sectional view.

Referring to FIG. 2, a female self-sealing connection 46 of known kind is attached to the upper end of a cylindrical tip 48 whose inner cavity 50 communicates with the connection 46 via a bore 52.

The inside surface of cavity 50 comprises a shoulder 54, and an intermediate ring 56, whose height is equal to the distance of the shoulder 54 from the bottom 58 of the cavity 50, is inserted in the cavity 50 bearing against the bottom 58.

Two resilient rings 60a, 60b of identical outside diameter are also introduced into the cavity 50. The ring 60a bears both against the shoulder 54 and the edge of the intermediate ring 56. The rings 60a, 60b are separated by a spacing washer 62 also introduced into the cavity 50.

A washer 64 is introduced into the cavity 50 to give the assembly 56, 60a, 62, 60b the compression produced by a hollow nut 66 screwed into a screwthreading 68 with which the lower inside portion of the cavity 50 is formed.

Locking screws, as 70, can extend through tappings, as 72, uniformly distributed around locking collar 74 of the hollow nut 66.

Referring again to FIG. 1, the operation of the apparatus described hereinbefore will now be analysed.

First of all the tank 1 is filled with 2-3 liters of inert liquid, inter alia a kerosene-based machining fluid, such as, for instance, "Lubrisurflex," which is therefore soluble in alcohol, compatible with NaK and of a lower density.

The lid 3 is placed on the tank, the argon inlet is connected to the connection 23 and the gas begins to circulate. The gas can circulate continuously and freely since the lid 3 has no gasket and is not sealing-tight and therefore allows the gas injected via conduit 25 to escape to the outside.

The inert liquid reservoir (not shown) is disposed pressurized in relation to the tank 1 and its valve remains closed.

A rotary roller-type pump (not shown), connected in series to the circuit to accelerate the circulation of the liquid, is stationary.

The upper portion of the irradiation capsule 35 which is disposed vertically in a vice (not shown) is cut off by a tube cutting machine or vertical sectioning machine. A few drops of inert liquid are poured into the capsule to cover the NaK.

The sealing-tight sleeve 7a is fitted and then locked on to the cut-off portion of the capsule 35 which is again sealing-tight and can be turned upside down, thus enabling its other end to be cut off like the first one. The sleeve 7b is then fitted on to this other end.

With the capsule 35 still retained vertically upside down the plug valve 5 is connected via its tube 41 to the connection 43b of the sleeve 7b. The capsule 35 is then turned over, valve downwards, whereafter the tube 17 of the valve 5 is introduced into the shaft 15 of the lid 3 and locked against rotation by the wing-type point screw 19.

The fluid inlet conduit 37 is connected to the connection 43a of the sleeve 7a.

After a number of vigorous flushings have been performed with pure inert liquid (1-2 liters), a few cm.³ of alcohol are added to the inert liquid remaining in the reservoir, at the rate of 1 cm.³ of alcohol to 1 cm.³ of NaK to be dissolved, and in the proportion of $\frac{1}{3}$ pure alcohol to $\frac{2}{3}$ inert liquid. The mixture is injected into the circuit and the dissolution of NaK begins.

To flush the capsule 35 more satisfactorily, the fluid inlet tube 37 and the plug valve 5 can be disconnected. The capsule containing the mixture of alcohol and inert liquid is then vigorously agitated, turned over and reconnected to continue the operation. The mixture again injected in the opposite direction has more chance of entraining the last traces of NaK trapped in "baffles."

The dissolution is monitored in the tank 1 by a thermometer probe disposed in the most suitable temperature measuring point 11 for the level of the liquid whose height, in the example given is 1 cm. per liter.

If the temperature exceeds 150° C., the argon flow into the tank is increased and a further quantity of pure inert liquid is injected as required.

If the temperature drops below 100° C., the reaction slows down, and alcohol slightly diluted with inert liquid can be re-injected, then pure alcohol. The liquid can also be vigorously agitated either with argon or mechanically, since agitation is indispensable for ensuring complete and rapid dissolution. Unless it is agitated the NaK, which is divided into small glomerules, is trapped in an alcoholate and foam film of the inert liquid and ceases to react with the alcohol.

To save time, after the pure alcohol has been injected, the capsule 35 can be disconnected and dismantling can begin while dissolution is terminating in the tank 1.

However, before disconnection a small amount of pure inert liquid can advantageously be injected which will insulate any traces of NaK from the air during the dismantling of the capsule.

The process and apparatus according to the invention are simple, direct and rapid and enable irradiation capsules containing 400 cm.³ NaK and above to be treated.

Safety is increased, since the alcohol used in small quantities is never pure in the presence of NaK, the temperature can be maintained at a low mean value of the order of 150° C., and the reaction can be readily controlled.

Time is saved by having a capsule available for dismantling before the completion of dissolution—i.e., half to one day after the start of the operation.

Raw material is saved, since the amount of alcohol required, which is clearly dependent on the amount of NaK to be dissolved, does not exceed 2-3 liters per 400 cm.³ of NaK. The inert liquid costs less than the alcohol, and the consumption of the former does not exceed 6-8 liters.

Lastly, the process and apparatus according to the invention enable sodium and/or potassium, which are solid at ambient temperature, to be emptied by directly re-heating the irradiation capsule with a heating strip.

Clearly, and as can be gathered from the foregoing, the invention is not limited to the method of application or the embodiment thereof which have been described and illustrated but, on the contrary, the invention covers all variants.

5 I claim:

1. A process for dissolving an irradiated metal selected from the group consisting of sodium, potassium, and an alloy thereof from an irradiation capsule which comprises:

- 10 (a) adding a sufficient amount of an inert liquid completely miscible with alcohol to said capsule to cover said irradiated metal,
- (b) adding a mixture of an alcohol and an inert liquid completely miscible with said alcohol to said capsule; and
- (c) vigorously agitating the mixture in said capsule to thereby dissolve said irradiated metal, said process being conducted under an argon atmosphere and the proportions of the alcohol being such that there is not an undesirably rapid rise in the temperature of said mixture due to reaction between said irradiated metal and said alcohol.

2. The process according to claim 1 wherein the temperature of said mixture is maintained between 100 and 150° C.

25 3. The process according to claim 1 wherein the volume ratio of alcohol to inert liquid is in the range of 1:2-4.

30 4. The process according to claim 1 wherein 1 cm.³ of alcohol is added per 1 cm.³ of said irradiated metal.

5. The process according to claim 1 wherein said capsule contains at least 400 cm.³ of said irradiated metal.

35 6. The process according to claim 1 wherein alcohol is used in an amount of 2-3 liters per 400 cm.³ of said irradiated metal in said capsule.

7. The process according to claim 1 wherein said step (a) is performed more than once by flushing said inert liquid from said capsule and then re-adding inert liquid such that said inert liquid covers said irradiated metal before said step (b) is conducted.
